UNITED STATES PATENT OFFICE.

CARL JOSEPH STRUVE, OF ELGIN, ILLINOIS.

JOURNAL-LUBRICATING SYSTEM.

Application filed August 23, 1924. Serial No. 733,679.

My invention relates to a system for lubricating the journal bearings in the journal box of a railroad car; the invention having for its object the provision of means whereby the journal bearings will be automatically lubricated while the car is in motion; the lubrication being continuously carried on regardless of the direction of travel of the car.

10 The objects and advantages of my invention will be more readily comprehended from the detailed description of the accompanying drawing, wherein:

15 Figure 1 is a sectional elevation of the end of the journal and the journal box with my improved lubricating system applied thereto.

20 Figure 2 is an enlarged longitudinal sectional view of the lower portion of a journal box and my lubricating system, with portions broken away.

Figure 3 is a sectional end elevation, taken substantially on the line 3—3 of Figure 1, looking in the direction of the arrows.

25 Figure 4 is a vertical sectional view taken substantially on the line 4—4 of Figure 1.

In the particular exemplification of the invention as disclosed in the drawing, the outer end of the journal is shown at 10, mounted in the usual journal box which is generally indicated at 11; the journal box being of the usual standard construction, provided with the Babbitt-metal 12 in direct contact with the journal 10 and beneath the brass 13 which is held in place by the usual wedge-block 14.

30 The bottom of the journal box is provided with a cylinder 15 of proper length and dimensions; the cylinder being shown preferably provided with nipples 16, 16 which are externally threaded and adapted to extend through suitable holes in the bottom of the journal box. The nipples are preferably provided with ports 17 in the sides to permit draining of the journal-box; 35 while the exterior ends of the nipples are provided with suitable caps 18 screwed thereon. The caps 18, not only firmly secure the cylinder in place but may also hold suitable washers in place on the nipples to provide fluid tight connection as shown in Figure 2; while the caps at the same time provide closures for the nipples; the nipples 16 being intended for draining and cleaning out the cylinder and the lower part of the 40 journal-box when occasion requires.

The ends of the cylinder 15 are shown preferably provided with removable caps 19 and 20, which screw onto the cylinder exterior and are preferably provided with the flanges having dished sides as shown in Figure 3, so as to provide suitable support for the ends of the cylinder and maintain it in spaced relation with the bottom of the journal-box, while at the same time preventing accidental unscrewing of the caps. The hub 45 of the cap 20 is shown socketed or provided with an internal bore to receive and provide bearing for the spindle or shaft 21 of a suitable spiral or feed screw 22 which is disposed lengthwise of the cylinder. The cap 70 19 is apertured and shown provided with a bushing 23 for the passage of the spindle or shaft 21.

50 The outer end of the spindle or shaft 21 is preferably angular in cross-section and 75 shown provided with a sprocket 24 which is slidably mounted on the spindle or shaft so as to rotate therewith and at the same time permit movement in keeping with the longitudinal movement of the journal. The 80 sprocket 24 is adapted to receive a sprocket chain 25 which extends about a sprocket 26 which is suitably secured to the end of the journal 10 so as to rotate with the journal; the sprocket 26 in the exemplification being 85 provided with a hub, extending from one side thereof, terminating in a flared portion or flange whereby the sprocket may be secured to the end of the journal as for example by means of suitable bolts or screws 90 as at 27 in Figure 1.

95 The cylinder 15, preferably, at a point intermediate of its ends, is provided with a plurality of openings 28 whereby the oil may enter or flow into the cylinder. With my improved system, the bottom of the journal box is intended to be filled with oil to a suitable level beneath the journal and the usual opening in the end wall of the journal box. The journal-box is preferably provided with a plate 29, suitably secured to the side walls of the box at a point above the oil level to prevent foreign matter falling into the oil chamber and also from entering the cylinder 15. The plate 29 is preferably dished toward the center so as to drain any excess oil, that may drip off the journal, into the oil holding portion of the box; the dished portion of the plate being provided with a suitable number of minute openings. 100 105 110

The cylinder 15 is thus fully immersed, thus causing the oil to enter the cylinder through the ports or openings 28.

The cylinder is shown provided with a pair of conduits 30 and 31 which are preferably arranged to communicate with opposite ends of the cylinder 15. These conduits or tubes 30 and 31 are arranged to extend toward the outer end of the journal-box and lead upward beyond the end of the journal 10; with the upper ends of the conduits or tubes arranged to communicate with or extend into suitable longitudinal passages arranged in the brass 13. These passages extend from the outer end of the brass preferably to a point intermediate of the ends, where the brass 13 with the Babbitt-metal 12 are both provided with a vertically disposed port or opening 32 extending through to the journal 10. The upper end of the port 32 in the brass 13 is shown preferably closed by a suitable plate as at 33 so as to induce the oil to flow out through the lower end of port 32 and therefore onto the end of the journal 10. The opening 32 is preferably of a size sufficient to retain a considerable quantity of oil discharged therein by either conduit 30 or 31; and in the event that the quantity of oil fed into the opening or well 32 is in excess of the oil being taken up by the bearings, the excess oil will flow back through the non-feeding conduit or tube, either 30 or 31 as the case may be, into the cylinder 15 and again forced through the feeding conduit, thus maintaining constant circulation and an economic use of oil.

With my improved construction, it is apparent that the oil entering the ports 28 of the cylinder 15 will be caused to travel toward one end of the cylinder when the spiral or feed-screw 22 is in operation; that is to say, when the car is in motion, rotation of journal 10 causes the screw or spiral 22 to be rotated through the medium of sprocket 26, sprocket chain 25 and sprocket 24, thereby forcing the oil toward one end of the cylinder 15 and therefore into the conduit or tube communicating with said end of the cylinder. Movement of the car and its journal in the opposite direction will cause the spiral to reverse its operation and therefore cause the oil to be fed toward the opposite end of the cylinder and upward through the tube communicating with said end; it being understood that the oil is forced through one conduit or tube at a time, depending upon the direction of travel of the car. The oil forced upward through the tube, passes through the respective longitudinal passage in the brass and empties into the port 32. In order that the oil may quickly find passage to the ends of the Babbitt-metal and thus ensure the entire bearing surface of the journal being fully lubricated, I prefer to provide the bottom surface

of the Babbitt-metal 12 with a suitable number of small grooves leading from the opening or well 32 toward the ends of the Babbitt-metal, as for example by employing grooves 34 radiating from the opening 32 and extending toward the corners of the metal, thus causing the entire bearing to be quickly lubricated.

In the particular exemplification, the tubes 30, 31 are each shown provided with a head or intermediate connection 35 to receive the portions of the tubes which are rigidly connected with the cylinder 15; although it is evident that the tubes may be made continuous and connected in any suitable way to the cylinder; the construction illustrated permitting easy assembly of the parts and also enabling the tubes to be replaced or the cylinder to be removed without disconnecting the upper ends of the tubes.

As is apparent from the construction shown in the drawing, an automatic oiling system for the car or journal box is provided which will ensure complete lubrication after the car or journal box has been supplied with a sufficient quantity of oil; the excess oil delivered at the top of the journal being allowed to pass through the non-feeding tube back into the cylinder from whence it is again forced through either one of the conduits or tubes. When the oil is to be renewed and the cylinder with the lower part of the journal box is to be drained, it is evident that removal of the caps 18, 18 will allow the oil to drain from the cylinder and also from the journal-box by means of the holes in the sides of the nipples, thus permitting a complete draining of the cylinder and the journal-box.

I have shown and described what I believe to be the simplest embodiment of my invention and have described the same in terms which are employed merely as terms of description and not as terms of limitation, as structural modifications are possible and may be made without, however, departing from the spirit of my invention.

What I claim is:

1. A system of the character described, comprising in combination with a journal-box, a cylinder located in the bottom of the journal-box and provided with clean-out nipples adapted to extend through the bottom of the journal-box, closures for said nipples, a spiral screw disposed lengthwise in the cylinder, inlet ports in the side wall of the cylinder for receiving the oil from the journal-box, conduits communicating with both ends of the cylinder and arranged to discharge the oil above the journal, and means intermediate of the journal and the spiral screw whereby the latter is rotated as the journal revolves and the oil caused to flow toward one end of the cylinder and through the respective conduit.

2. In a system of the character described, the combination of a journal-box, the lower part whereof is adapted to be filled with oil, a brass provided with longitudinal ports 5 terminating in a common port extending through to the bottom of the brass, a cylinder located in the bottom of the journal-box and provided with inlet ports in the side wall for admitting oil into the cylinder 10 from the journal-box, an outlet from the cylinder disposed through the wall of the journal-box whereby the cylinder is removably held in place and the oil may be drained, a pair of conduits extending from 15 opposite ends of the cylinder and communicating with the ports in the brass, a feed-screw rotatably mounted in the cylinder adapted to force the oil toward either end of the cylinder, the spindle of the feed-screw 20 being disposed through the end wall of the cylinder and provided with a sprocket slidably mounted thereon, a sprocket secured to the outer end of the journal, and a chain disposed about the sprockets on the 25 feed-screw spindle and on the journal whereby the feed-screw is rotated in the same direction as the journal revolves.
3. In a system of the character described, a cylinder provided with a clean-out portion 30 adapted to extend through the bottom of a journal-box and be secured thereto, inlet ports in the side wall of the cylinder, a feed-screw located in the cylinder, closure means for the ends of the cylinder adapted to provide bearings for the spindle of the feed-screw, a conduit connected with each end of the cylinder and arranged to discharge the oil onto the journal, and driving mechanism intermediate of the spindle of the feed-screw and the journal whereby the feed-screw is rotated as the journal revolves.
4. In an oiling system of the character described, the combination of a journal-box in which the end of a journal is rotatably mounted, a cylinder located in the bottom of the journal-box and provided with nipples disposed through the bottom of the journal-box, the nipples being provided with openings in the side for draining the bottom of the journal-box, closures for the outer ends of the nipples whereby the cylinder is clamped in place, oil admitting ports in the cylinder, conduits leading from opposite ends of the cylinder for conveying the oil onto the journal, a feed-screw in the cylinder, and means intermediate of the feed-screw and the journal whereby the screw is rotated and oil forced through one or the other of said conduits.

CARL JOSEPH STRUVE.
